(57) CLAIM

I claim the ornamental design for an accessory auto lamp, as shown and described.

DESCRIPTION

FIG. 1 is a perspective view of an accessory auto lamp according to my new design;

FIG. 2 is a front view thereof;

FIG. 3 is a rear view thereof;

FIG. 4 is a right side view thereof;

FIG. 5 is a top view thereof; and,

FIG. 6 is a bottom view thereof.

The broken line showing of in FIGS. 1, 2 and 6 is included for the purpose of illustrating unclaimed matter and forms no part of the claimed design.
